UNITED STATES PATENT OFFICE.

FREDERICK O. HILFIKER, OF SYRACUSE, NEW YORK, ASSIGNOR TO F. O. HILFIKER CO., OF SYRACUSE, NEW YORK, A CORPORATION OF NEW YORK.

TOILET IMPLEMENT.

1,205,894.

Specification of Letters Patent. Patented Nov. 21, 1916.

Original application filed April 7, 1911, Serial No. 619,518. Divided and this application filed December 9, 1912. Serial No. 735,634.

To all whom it may concern:

Be it known that I, FREDERICK O. HILFIKER, of Syracuse, in the county of Onondaga and State of New York, have invented 5 certain new and useful Improvements in Toilet Implements; and I do hereby declare the following to be a full, clear, and exact description of the same, reference being had to the accompanying drawings, forming a 10 part of this specification, and to the reference numerals marked thereon.

My present invention relates to toilet apparatus, and more particularly to massage implements, and it has for its object to provide a device of that character in the nature 15 of a flesh brush that will be suitable for general massage purposes, lathering for shaving or for use in the bath, particularly in connection with a spray head.

20 A further object of the invention is to provide improved means for retaining the flexible brush in the head or holder by which it is carried.

To these and other ends the invention consists in certain improvements and combinations of parts all as will be hereinafter more 25 fully described, the novel features being pointed out in the claims at the end of the specification.

30 In the drawings, Figure 1 is a bottom plan view of a massage implement constructed in accordance with and illustrating one embodiment of my invention, and Fig. 2 is a central section taken substantially on the 35 line 2—2 thereof.

Similar reference numerals throughout the several figures indicate the same parts.

In the present embodiment of the invention, the massage brush is in the nature of 40 an attachment to a spray head or rose such as is used for bathing purposes as this application is a division of my prior application, Serial No. 619,518, filed April 7, 1911, and for the latter reason, a specific description 45 of the spray head which constitutes the holder in the present instance, and is claimed in the other case, is not required. Suffice it to say, therefore, that it may comprise a hollow head 1 annular in shape with a flat 50 foraminous bottom face 2 providing a plurality of jet openings that jointly produce a hollow cylindrical stream or spray. The head is suitably attached to a ring 3, the terminals of which form a two-part handle 4

and between these handle portions is run 55 the supply pipe 5 connected to the head at 6.

In the practice of my present invention, the head 1 is fitted with a flesh brush or massage element 7 that is seated within the central opening or socket 8 of the head. I 60 prefer to construct this brush of reasonably soft and pliable rubber and cup-shaped, as clearly shown in Fig. 2. The integral rubber bristles 9 project from the under or outer side of the bottom 10 of the cup, while the 65 side wall or rim 11 is thrust within the socket or opening 8 of the head and, as it is compressed when so inserted, its expansive force and the clinging nature of the material causes it to firmly and frictionally grip the 70 walls of the opening with sufficient force to retain the brush in its seat during all ordinary manipulations, though it may be easily and quickly removed with the fingers by compressing it as it is pulled outwardly. 75 The walls of the socket or opening 8 are preferably tapered and the brush is held in the small end so that it will respond with a wedging action upon the exercise of any force tending to pull it from its seat. To 80 make its position even more secure, the brush and socket or, at least, the rim or retaining portion of the latter, may be provided with coöoperating shoulders 12 and 13, respectively, that engage and interlock, in 85 the manner shown in Fig. 2. The shoulder on the rubber cup also gives greater body to its retaining portion and renders its expansive tendency more effective.

The brush may be inserted from the top 90 or larger side of the opening 19 in the head, in the embodiment shown, by thrusting it through the latter, bristles first, but ordinarily it may be safely made sufficiently small to insert it from the other side by 95 crowding the flanged portion or rim thereof inwardly. The removability of the brush permits different ones having different characteristics to be interchanged as conditions require, as for instance, coarse and fine 100 brushes may be provided with each implement. Also, the brush may be discarded if it is wished to use the spray head or other compound instrument to which the brush is fitted, alone, or the brush may be itself 105 used alone for massage purposes with or without disconnecting the supply pipe from the head in the present embodiment.

It is again pointed out that the massage brush need not necessarily be connected to a head of the nature described as a plain or other head or holder may be employed, but 5 one preferably fitted with a socket formed similarly to the socket 8 of the present device.

I claim as my invention:

1. The combination with a head having 10 a central opening therein extending entirely through the head, of a removable cup-shaped flesh brush composed of flexible material arranged within the opening and comprising an inwardly compressible rim portion frictionally engaging the walls of the head, and 15 a relatively transversely extending flexible bristle carrying body portion offset outwardly from the rim portion.
2. The combination with a head having 20 a central tapered opening, of a removable cup-shaped flesh brush composed of flexible material, arranged within the smaller end of the opening and having its inwardly compressible rim portion frictionally engaging 25 the inclined walls of the latter, the body

of the brush being also sufficiently flexible to permit of distortion adapting it to be thrust through the opening from the larger side thereof.

3. The combination with a head having 30 a central opening therein, provided with a shoulder on its walls, of a removable cup-shaped flesh brush composed of flexible material arranged within the opening and having its inwardly compressible rim portion 35 frictionally engaging the walls of the latter beyond the shoulder.

4. The combination with a head having a central opening therein, of a removable cup-shaped flesh brush composed of flexible 40 material arranged within the opening and having its inwardly compressible rim portion frictionally engaging the walls of the latter, and coöperating retaining shoulders on said rim and the walls of the opening.

FREDERICK O. HILFIKER.
